UNITED STATES PATENT OFFICE.

HADLEY F. FREEMAN, OF MILWAUKEE, WISCONSIN.

WRAPPING MACHINE.

Application filed October 9, 1922. Serial No. 593,468.

My invention relates to machinery and the principal object of my invention is to provide new and improved machinery for various uses. In the drawings accompanying this specification and forming a part thereof I have shown, for purposes of illustration, three forms which my invention may assume. In these drawings:

Figure 1 is a front elevation of one of these forms,

Figure 2 is a side elevation of the form shown in Figure 1,

Figure 3 is a section on the line 3—3 of Figure 1,

Figure 4 is a section similar to Figure 3 but showing the second form,

Figure 5 is a detailed view of a portion of this second form,

Figure 6 is a view similar to Figure 1 showing a third form,

Figure 7 is a section on the line 7—7 of Figure 6.

The machine shown in Figures 1, 2, and 3 comprises an electric stator 11 mounted on a suitable base 12 and provided with a gap 13 which may be bridged by a pair of U shaped pieces 14 serving to complete the magnetic circuit of the stator 11 and either wound with a continuation of the stator 30 winding 15 suitably attenuated to provide the same number of poles as would be provided were the stator continued directly across the gap 13 or else unwound as shown in the drawings in which the stator winding 35 is shown as terminating at the edges of the gap 13. Suitably mounted in the stator 11 are a pair of bearing rings 16 made of any suitable non-magnetic material such as non-magnetic steel and adapted to provide race-

ways for roller bearings 17 co-operating race-ways for which consist of a pair of similar non-magnetic rings 18 fixedly secured to and supporting a rotor 19 which is preferably of the squirrel cage type provided with bars 20 and slotted to provide a gap 34 adapted to co-operate with the gap 13 in the stator 11. Suitably mounted in a depression 21 in the rotor 19 is a detent or dog 22 pivoted to the rotor at 23 and provided with a tooth 24 adapted to engage a shoulder 25 in the stator 11 when the dog is forced outwardly under the action of a compression spring 26 but also provided with a

weighted reverse end 27 adapted to be thrown outwardly during rotation of the 55 rotor until the tooth 25 lies in the depression 28 in the rotor 19 and the entire dog is carried out of contact with the stator 11. In the drawings the machine above described is shown as wound for three-phase current 60 and is controlled by a three-pole switch 29 provided with a running position 30, a neutral position 31, and a reverse position 32. This switch may conveniently take the form of a foot operated switch biased to reverse 65 position in any suitable manner as by a spring or gravity and operable through neutral position into forward position.

The dynamo electric machine above described is set in motion by moving the switch 70 29 into forward position whereupon the current is supplied to the stator winding 15 and the rotor 19 caused to rotate counter-clockwise or in the direction of the arrow as shown in Figure 1. So long as rotation of 75 the rotor is desired the switch is held in this forward position but when it is desired to stop the rotor the switch is released and moves through neutral position into the reverse position whereupon a low voltage current is supplied to the stator winding 15 through the transformers 33 to rapidly stop the rotor and then start it rotating in the reverse direction. When the rotor stops, however, the spring 26 will act to press the tooth 80 24 of the dog 22 outwardly so that at the first opportunity during reverse movement of the rotor this tooth will engage the shoulder 25 of the stator 11 and bring the rotor to rest at that point at which the gap 34 85 90 therein is aligned with the gap 13 in the stator 11.

While I may utilize this machine for a variety of purposes I have in mind the utilization thereof for wrapping annular articles 95 such as automobile casings and for this purpose I have provided the machine with a pair of concaved rollers 35 supported on shafts 36 seated in bearings 37 carried by brackets 38 and 39 adjustably mounted upon 100 the U shaped pieces 14 of the stator 11 by means of bolts 40 screw-threaded into the U shaped pieces 14 and passing through slots 41 in the brackets 38 and 39. The brackets 39 are provided with extensions 42 provided 105 with bearings 43 adapted to support shafts

44 carrying at their inner ends pinions 45 meshing with gears 46 carried by the shafts 36 and at their outer ends bevel gears 47 meshing with co-operating bevel gears 48 carried by a cross-shaft 49 which also carries a drum 50 adapted to be engaged and driven by a belt 51 passing over a train of pulleys 52 and then around a portion of a belt ring 53 carried by the rotor 19 whereby 10 the pulleys 35 are driven by the rotor 19 at a speed bearing a fixed relation to the speed of the rotor 19 so that a casing 54 supported by the rollers 35 will be advanced a fixed distance for each rotation of the rotor. 15 Rising from the stator 11 are a pair of uprights 54 provided at their upper ends with offsets 55 carrying a shaft 56 on which is pivotally mounted a weighted arm 57 carrying at its free end a roller 58 similar to the 20 rollers 35 and adapted to engage the upper outer periphery of the casing 54 to hold the casing in firm engagement against the rollers 35. It will be understood that this roller 58 may also be driven if desired and also 25 that the drive may be omitted from one of the rollers 35 and in general that the casing may be driven in any suitable manner.

Suitably mounted upon the rotor 19 in any desired manner as by means of a shaft 30 59 carried by brackets 60 mounted on the rotor 19 is a roll 61 of wrapping material 64 adapted to be wound about the tire 54 and to be restrained from undue movement by a friction brake 62 applied to the periphery thereof and carried by the rotor 19 in any manner operative to cause it to continuously press against the roll 61 as by a leaf spring 63.

40 It will be understood from the above description that with the rotor at rest the casing 54 is placed in position and the end of the wrapper 64 held in position upon the casing after which the switch 29 is operated to cause rotation of the rotor and thereby cause the wrapper 64 to wrap about the casing 54 while the casing 54 is uniformly advanced to cause a uniform spiral of paper to be applied to the casing to form a continuous covering therefor. After this wrapping has progressed completely around the casing 54 the switch 29 is returned to reverse position whereupon the rotor 19 is rapidly stopped and brought into position with its gap 34 aligned with the gap 13 of the stator 11 and the wrapped casing removed and an unwrapped casing substituted ready for a subsequent operation.

60 It will be understood that the brackets 38 and 39 are adjustable vertically to permit vertical adjustment of the rollers 35 whereby these rollers may support any size tire exactly centrally of the rotor and thus eliminate vibration which might result from eccentric support of the casing. It will be understood that the drive between the belt

ring 53 and the roller 50 is such that these adjustments may be made without any change in this drive although if necessary a compensating pulley may be employed to take up any slack in the belt 51 because of 70 change in position of the drum 50. It will also be understood that the wrapping material 64 may be provided other than in a roll and that the roll may be otherwise supported and that the wrapping material may be 75 passed through any suitable train of devices before it reaches the casing 54. It will also be understood that the rotation of the rotor may be controlled in any other suitable manner and also that the within control may be 80 applied to other types of machines.

In Figures 4 and 5 I have shown portions of a machine similar to the machine shown in Figures 1, 2, and 3 but differing from that machine in that the rotor 70 instead of being 85 supported from the stator 71 is supported from an internal annular segmental bearing 72 by means of two sets of roller bearings 73. This internal bearing 72 is in turn supported by a bracket 74 preferably integral 90 therewith and secured to the base 75 in any suitable manner as by welding.

In Figures 6 and 7 I have shown a third form in which the stator 80 is positioned within the rotor 81 which is mounted thereon in any suitable manner as by means of roller bearings 82 engaging non-magnetic rings 83 and 84 carried by the stator 80 and rotor 81 respectively. The stator 80 is also provided with a depending arm 85 secured 100 to the base 86 and with suitable U shaped members 87 adapted to complete the magnetic circuit of the stator 80 and to also serve as a bearing for a roller 88 similar to the rollers 35 and adapted to be driven in substantially the same manner. The base 86 also carries a second arm 89 adapted to support a second roller 90 arranged to co-operate with the roller 88 to support the casing 54 and adapted to be also driven in any 110 suitable manner if so desired. The wrapping mechanism is shown in the form of a roll 91 mounted upon a shaft 92 carried by a bracket 93 positioned upon the rotor 84 in offset position.

115 It will be understood that if desired the rotor may also be provided with U shaped members to complete the magnetic circuit thereof, that the loop completing the magnetic circuit of the stator may be omitted 120 if desired, that this stator loop if used may be wound to continue the stator winding, and that the electric machine and in fact the entire machine herein disclosed may be used for other purposes and controlled in other ways while the control herein disclosed may be used on other machines. In addition to this the method of supporting the rotor, the article support and feed, and the paper support and feed, are all illustrative only and 125 130

in general this entire disclosure is illustrative only and my invention is not limited thereto.

I claim:

- 5 1. A machine comprising an electric stator, an electric rotor formed to permit the placement of an article in position to be wrapped, and means carried by said rotor arranged to support wrapping material in 10 position to wrap said article upon rotation of said rotor.
- 15 2. Article wrapping mechanism, comprising a rotary electric motor, and means carried by the rotating element of said motor formed to carry material for wrapping the article upon rotation of said element.
- 20 3. Article wrapping mechanism, comprising a rotary electric motor having an annular rotating element formed to permit the presence within said element of a part of the article to be wrapped, and means carried by said element formed to carry material for wrapping said article upon rotation of said element.
- 25 4. Article wrapping mechanism, comprising a rotary electric motor having a segmental annular rotating element formed to permit insertion, through the gap in said element, of a part of the article to be wrapped, and the presence of said part within said element, and means carried by said element formed to carry material for wrapping said article upon rotation of said element.
- 30 5. Article wrapping mechanism, comprising a rotary electric motor having segmental annular stationary and rotating elements formed to permit the insertion, through the gap in said elements, of a part of the article to be wrapped, and the presence of said part within said elements, and means carried by said rotating element formed to carry material for wrapping said article upon rotation of said rotating element.
- 35 6. Article wrapping mechanism, comprising a rotary electric motor having segmental annular stationary and rotating elements formed to permit the insertion, through the gaps in said elements, of a part of the article to be wrapped, and the presence of said part within said elements, the open ends of said stationary element being connected by a path of low reluctance displaced to permit such insertion and presence, and means carried by said rotating element formed to carry material for wrapping said article upon rotation of said rotating element.
- 40 7. Article wrapping mechanism, comprising a rotary electric motor having segmental annular stationary and rotating elements formed to permit the insertion, through the gaps in said elements, of a part of the article to be wrapped, and the presence of said part within said elements, the open ends of said stationary element being connected by paths of low

reluctance displaced to permit such insertion and presence, and means carried by said rotating element formed to carry material for wrapping said article upon rotation of said rotating element.

70 8. Article wrapping mechanism, comprising a rotary electric motor having segmental annular stationary and rotating elements formed to permit the insertion, through the gaps in said elements, of a part of the article to be wrapped, and the presence of said part within said elements, the open ends of said stationary element being connected by a path of low reluctance displaced to permit such insertion and presence, means carried by said rotating element formed to carry material for wrapping said article upon rotation of said rotating element, and means carried by said path to support the article being wrapped.

75 85 90 95 100 105 110 115 120 125 130 9. Article wrapping mechanism, comprising a rotary electric motor having a segmental annular rotating element formed to permit insertion, through the gap in said element, of a part of the article to be wrapped, and the presence of said part within said element, means carried by said element formed to carry material for wrapping said article upon rotation of said element, and means for controlling the rotation of said element arranged to automatically align said element, upon cessation of rotation thereof, in position to permit insertion or withdrawal of said article through said gap.

10. Article wrapping mechanism, comprising a rotary electric motor having segmental annular stationary and rotating elements formed to permit the insertion, through the gaps in said elements, of a part of the article to be wrapped, and the presence of said part within said elements, means carried by said rotary element formed to carry material for wrapping said article upon rotation of said rotating element, and means for controlling the rotation of said rotating element arranged to automatically position said rotating element, upon cessation of rotation thereof, with its gap in alignment with the gap in said stationary element.

11. Article wrapping mechanism, comprising a rotary electric motor having an annular rotating element formed to permit the presence within said element of a part of the article to be wrapped, means carried by said element formed to carry material for wrapping said article upon rotation of said element, and means actuated by said element arranged to advance said article upon rotation of said element.

12. Article wrapping mechanism, comprising a rotary electric motor having a segmental annular rotating element formed to permit insertion, through the gap in said element, of a part of an article to be

wrapped, and the presence of said part within said element, means carried by said element formed to carry material for wrapping said article upon rotation of said element, and means actuated by said element arranged to advance said article upon rotation of said element.

13. Article wrapping mechanism comprising a shuttle arranged to be positioned 10 to permit introduction and withdrawal of the article, means for operating said shuttle arranged, upon cessation of wrapping action, to cause slow retrograde movement of said shuttle, and means arranged to halt said 15 retrograde movement with said shuttle so positioned to permit such introduction and withdrawal.

14. Article wrapping mechanism comprising a shuttle arranged to be positioned 20 to permit introduction and withdrawal of the article, an electric motor for operating said shuttle, a switch arranged to cause normal forward movement of said motor or slow speed retrograde movement of said 25 motor, and means arranged to halt said retrograde movement with said shuttle so

positioned to permit such introduction and withdrawal.

15. Article wrapping mechanism comprising a shuttle arranged to be positioned 30 to permit introduction and withdrawal of the article, means for operating said shuttle arranged, upon cessation of wrapping action, to cause slow retrograde movement of said shuttle, and means arranged to halt 35 said retrograde movement positively and with said shuttle so positioned to permit such introduction and withdrawal.

16. Article wrapping mechanism comprising a shuttle arranged to be positioned 40 to permit introduction and withdrawal of the article, an electric rotor for operating said shuttle, a switch arranged to cause normal forward movement of said motor or 45 slow speed retrograde movement of said motor, and means arranged to halt said retrograde movement positively and with said shuttle so positioned to permit such introduction and withdrawal.

In testimony whereof I have signed my 50 name to the above specification.

HADLEY F. FREEMAN.
